CLAIM

The ornamental design for a dog house, as shown and described.

DESCRIPTION

FIG. 1 is a perspective view of a dog house showing my new design;

FIG. 2 is a front elevational view thereof;

FIG. 3 is a rear elevational view thereof;

FIG. 4 is a left side elevational view thereof, the right side being a mirror image of the left side shown;

FIG. 5 is a cross-section view thereof taken along line 5—5 of FIG. 2.

FIG. 6 is a top plan view thereof;

FIG. 7 is a bottom plan view thereof;

FIG. 8 is another perspective view of a second embodiment of FIG. 1;

FIG. 9 is a front elevational view of FIG. 8;

FIG. 10 is a rear elevational view of FIG. 8;

FIG. 11 is a left side elevational view of FIG. 8, the right side being a mirror image of the left side shown;

FIG. 12 is a cross-sectional view taken along line 12—12 of FIG. 9.

FIG. 13 is top plan view thereof;

FIG. 14 is a bottom plan view thereof;

FIG. 15 is another perspective view of a third embodiment of FIG. 1;

FIG. 16 is a front elevational view of FIG. 15;

FIG. 17 is a rear elevational view of FIG. 15;

FIG. 18 is a left side elevational view of FIG. 15, the right side being a mirror image of the left side shown; and

FIG. 19 is a cross-sectional view taken along line 19—19 of FIG. 16.

The broken line representation of a strip and insignia on FIGS. 8-11, 13, 15-18, and 20 is for illustrative purposes only and forms no part of the claimed design;

FIG. 20 is a top plan view thereof; and

FIG. 21 is a bottom plan view thereof.
